DESIGN FOR A BATHING SANDAL

George B. Carrier, Hudson, Mass., assignor to Firestone Footwear Company, Boston Mass.,
a corporation of Massachusetts

Application May 3, 1932. Serial No. 43,705

Term of patent 14 years

To all whom it may concern:

Be it known that I, GEORGE B. CARRIER, a citizen of the United States, residing at Hudson, in the county of Middlesex and State of Massachusetts, have invented a new, original, and ornamental Design for a Bathing Sandal, of which the following is a specification, reference being had to the accompanying drawing, forming a part thereof.

In the drawing:

The figure is a perspective view of a bathing sandal, showing my new design.

I claim:

The ornamental design for a bathing sandal as shown.

GEORGE B. CARRIER.
